UNITED STATES PATENT OFFICE

2,227,920

VENTILATED TOILET

Harry Baither, Milwaukee, Wis.

Application March 15, 1939, Serial No. 261,902

8 Claims. (Cl. 4—213)

This invention appertains to bathroom appliances, and more particularly to toilets of the general type illustrated in my Patent No. 1,931,052, issued to me October 17, 1933.

5 One of the primary objects of my invention is to provide novel means for constructing a ventilated toilet in such a manner that all objectionable odors will be carried off from the toilet bowl to the drain pipe while the toilet is in use, and 10 all danger of foul odors seeping back from the drain pipe into a room is eliminated.

Another salient object of my invention is the provision of a ventilated toilet bowl having a water seal or trap chamber therein for the foul 15 odors, with means for normally preventing the escaping of all odors or gases therefrom, means being provided for creating a pressure in said chamber to force gases containing foul odors collected in said chamber to the drain pipe.

20 Another important object of my invention is the provision of an electric motor and fan for taking the gases from the bowl and for creating pressure in said water seal trap chamber and for mounting the motor and fan in such a manner 25 that the same will be normally hidden from view.

A further object of my invention is the provision of novel means for mounting the fan and motor on the toilet in such a manner that noise and vibrations will be reduced to a minimum.

30 A still further object of my invention is to provide a ventilated toilet of the above character, which will be durable and efficient in use, and one in which the parts are compactly and conveniently arranged.

35 With these and other objects in view, the invention consists in the novel construction, arrangement, and formation of parts, as will be hereinafter more specifically described, claimed, and illustrated in the accompanying drawings, 40 in which drawings:

Figure 1 is a vertical sectional view through my complete ventilated toilet, the view being taken substantially on the line 1—1 of Figure 2, looking in the direction of the arrows.

45 Figure 2 is a transverse sectional view through the toilet, taken on the line 2—2 of Figure 1, looking in the direction of the arrows.

Figure 3 is an enlarged, detail, sectional view 50 illustrating the means for automatically closing the circuit through the electric motor when pressure is applied to the seat of the toilet.

Figure 4 is a horizontal sectional view taken 55 on the line 4—4 of Figure 1, looking in the direction of the arrows, illustrating the means of incorporating the vent pipe with the drain pipe.

Figure 5 is an enlarged, detail, sectional view taken on the line 5—5 of Figure 1, looking in the direction of the arrows, illustrating one means employed for resiliently mounting the motor and fan in place.

5 Figure 6 is a fragmentary, vertical, sectional view through a slightly modified form of my toilet, the view being taken on the line 6—6 of Figure 7, looking in the direction of the arrows.

Figure 7 is a transverse, sectional view taken 10 on the line 7—7 of Figure 6, looking in the direction of the arrows.

Figure 8 is a detail sectional view taken on the line 8—8 of Figure 9, looking in the direction of the arrows, illustrating the means of incorporating the fan and motor in a compartment formed integral with the water tank or reservoir.

Figure 9 is a sectional view through the water tank or reservoir, taken on the line 9—9 of Figure 8, looking in the direction of the arrows.

Figure 10 is a detail, horizontal, sectional view taken on the line 10—10 of Figure 9, looking in the direction of the arrows, showing the compartment formed in the water tank and the means for mounting the fan and motor in said compartment.

30 Referring to the drawings in detail, wherein similar reference characters designate corresponding parts throughout the several views, the letter T generally indicates my improved ventilated toilet, which comprises a toilet bowl 15, having communicating therewith, through a water seal or trap 16, a drain pipe 17. This drain pipe 17 is connected through the medium of a suitable coupling (not shown) with the drain pipe of a building.

35 The upper end of the bowl 15 has formed therein a flush ring 18. The flush ring 18 has communicating therewith a plurality of outlet apertures 19, and the flush ring communicates with the main water outlet 20 of the flush tank 21. This outlet 20 also communicates through an enlarged passageway 22 with the body of the bowl 15. The flush tank 21 can be formed integral with or separated from the bowl 15. The passageway 20 can be controlled in the usual or any preferred manner by a valve 23.

40 In accordance with my invention, I form in the rear end of the bowl in back of the outlet or drain pipe 17 and the passageway 22, a water seal or trap chamber 24, and this chamber is adapted to be supplied with water through a small pipe 25, which extends down toward the bottom of the chamber and opens into the passageway 22. Thus, when the passageway 22 is supplied with 45

water, water will also be supplied to the trap chamber 24.

Leading from the trap chamber 24 at the desired water level is a vent pipe 26. This vent pipe 26 is carried into the discharge or drain pipe 17 adjacent the lower end thereof, and, if desired, this vent pipe 26 can be of an oval shape in cross-section, and the inner wall of the discharge or drain pipe 17 can be hollowed out to receive the same. This will make a smooth inner drain pipe contour, so that foreign objects will not adhere to the pipe.

Also extending into the trap chamber 24 through the upper wall thereof is an inverted gooseneck pipe 27, which forms a water seal or trap. The free end of the pipe 27 extends slightly above the upper end of the vent pipe 26, and, if desired, a splash plate 28 can be arranged in front of the open end of the vent pipe, so that if undue disturbance is caused in the water of the chamber, the water will not have a tendency to unduly drain from the chamber through said pipe 26.

In the form of my invention shown in Figures 1 to 5 inclusive, the usual or conventional type of flush tank 21 is employed, and in accordance with my invention, I place in said tank at the desired point, a casing 29 for housing the electric motor 30 and the fan 31. The casing 29 is provided with a removable cover 32 above the water line of the flush tank, so that entrance into the casing can be had when necessary or desirable.

To reduce noise and vibration, the casing is suspended in the flush tank by means of shock absorbing coil springs. Certain springs 32' can be disposed between the bottom of the casing 29 and the flush tank, and certain springs 33 can be arranged between the front of the casing 29 and the front wall of the flush tank. Other springs 34 can be arranged between the rear wall of the casing and the rear wall of the flush tank.

In order to further reduce noise and vibration, the fan and motor 30 and 31 are arranged together as a unit, and this unit is then suspended in the casing by means of coil springs 35, as is clearly shown in Figures 1 and 2. The intake 36 of the fan 31 has connected thereto a suction pipe 37, which leads into the toilet bowl and communicates with the chamber 22, so that when the fan is running, a suction will be created in the bowl through the openings 19 and the flush ring 18. The outlet of the fan is connected to a pipe 38, which leads to the gooseneck 27. The inlet and outlet pipes 37 and 38 have incorporated in their lengths at the desired points flexible couplings 39. These couplings prevent vibrations and noise from being transmitted from the motor and fan to the casing 29, and from the casing 29 to the flush tank and bowl. In order to insure the proper filling of the gooseneck with water to form the water seal, one branch thereof has formed therein a small opening 40 below the normal water level in said trap chamber 24.

The usual flush tank pipe 41 can be provided with a water trap 42, which prevents the drawing of air through the pipe while the fan is in operation. Thus, all of the air is sucked from the bowl through the flush ring.

The circuit to the electric motor 30 can be closed in any preferred manner, and the current for operating the motor can be derived from the house circuit. In order to make the opera-

tion of the device automatic, I propose to close a switch to the motor 30 when the pressure is placed upon the seat 43 of the toilet bowl.

The seat 43 at its rear end is provided with hanger hinges 44, which are mounted upon hinge pins 45. These hinge pins are carried by brackets 46 slidably mounted on the top of the bowl. The brackets 46 are normally held in a raised position by expansion coil springs 47 placed about the brackets and confined between shoulders 48 on the brackets and the top of the bowl. One of the brackets 46 is employed as the operating device for the switch, and, consequently, this bracket is guided in a sleeve or bearing 49 carried by the top of the bowl 15. The lower end 15 of the sleeve 49 has firmly secured thereto an insulating housing 50. Firmly secured to the lower wall of the insulating housing is an electric contact 51 and a companion contact 52 is carried by, but insulated from the sliding bracket. The contacts 51 and 52 have electrically connected thereto current-conducting wires 53 and 54. These wires can be led through a conduit 55 disposed in the flush tank 21, and the conduit, in turn, can lead into the casing 29 to the motor. This conduit can also be provided with a flexible coupling 56, so that vibrations will not be transferred along the length of the pipe. Obviously, at a desired point, electrical connections can be made with the electrical wires 53 and 54 with the wires of the house circuit.

In operation of my improved device, when pressure is placed upon the seat 43, the rod 46 carrying the contact 52 will be lowered, and this contact will be carried into engagement with the contact 51, and the circuit will be automatically closed with the motor 30. The fan 31 will draw all objectionable odors from the bowl through the flush ring, and air containing the foul odors will be forced under pressure into the chamber 24. This pressure will blow the water out of the gooseneck 27, and the air containing the foul odors will be forced into the pipe 26, and thence into the drain pipe. As soon as the circuit is broken, the fan 31 will cease its operation, and, consequently, the pressure in the chamber 24 will be relieved. The water seal will again be formed in the pipe 27 by flowing into the pipe through the opening 40.

By this construction and arrangement, a simple and inexpensive means is provided for carrying off of vile odors without any danger of foul gases leaking back into a room from the toilet bowl.

If preferred, an expansion spring 57 can be interposed between the contacts 51 and 52 to insure the normal operation thereof, and means is employed for insuring the proper insulation of the spring from the contacts.

In Figures 1 and 2, I have shown the fan and motor mounted in a casing within the flush tank. Some manufacturers may desire to form the flush tank, the bowl, and the compartment for the fan and motor, as well as the trap chamber, all in one piece.

In Figures 6 and 7, I have illustrated one convenient arrangement of this type. As shown in these two figures, the bowl and flush tank 60 and 61, at their point of juncture and at the rear face thereof, are provided with a compartment 62. This compartment 62 opens out through the rear of the bowl and tank, and can be normally closed by a removable cover plate 63. In this compartment is disposed the motor 64 and fan 65. The motor and fan unit is suspended in the compartment 62.

ment by the use of suitable coil springs 66, which are disposed at the desired appropriate points. The intake pipe 67 for the fan communicates with the flush chamber 60 of the bowl, so that a suction 5 will be formed in said chamber and in the flush ring 68. This pipe 67 is formed relatively high so as to eliminate back pressure therein. The outlet 69 of the fan communicates with the trap chamber 70 through a gooseneck 71. The chamber 70 10 is supplied with water from the flush chamber 60 through the medium of a pipe 72. The outlet from the compartment 70 includes a short length of pipe 73, which communicates with a second chamber 74 formed in the bowl, and the said 15 second chamber then communicates with the drain pipe 75 by a short length of tubing 76. This form of my invention operates the same as that form just previously described.

In Figures 8 to 10 inclusive, I have illustrated 20 an arrangement whereby a compartment can be formed integral with a flush tank 80. As shown in the mentioned figures, the rear wall of the flush tank 80 can have built thereon an enclosing wall 81, which wall, cooperating with the rear wall of 25 the flush tank and the bottom wall of the flush tank, forms a compartment 82 for the motor 83 and the fan 84. The motor and fan unit is suspended in the compartment by springs 85, and the inlet and outlet of the fan is connected with 30 the other parts of my ventilated toilet in the same manner as the two forms of my invention previously described.

In all instances, the inlet and outlet tubes and 35 other pipes leading from the fan and motor have flexible couplings incorporated therein.

Changes in details may be made without departing from the spirit or the scope of my invention, but what I claim as new is:

1. A ventilated toilet comprising, a bowl having 40 a water basin therein and a drain pipe below the basin and communicating therewith, means for creating a suction in said bowl above the water basin including an electric motor and a fan, a closed trap chamber, means for supplying water 45 to a predetermined level to said trap chamber upon the flushing of the bowl, a vent pipe entirely independent of the motor and fan connecting the chamber with the drain pipe and extending a predetermined distance into said chamber, an inverted 50 gooseneck disposed in said chamber having one end extending above the normal water level in said chamber and its other end communicating with the discharge of the fan, whereby upon operation of the fan and the creation of the 55 suction in the bowl, a pressure will be created in the trap chamber to force gases through the vent pipe, said gooseneck having a water entrance therein to insure the forming of a water seal therein.

2. In a ventilated toilet, a flush tank having an 60 integral compartment formed in the interior thereof, an electric motor and suction fan resiliently suspended in said compartment, and a cover for the flush tank closing said compartment.

3. A toilet bowl having a discharge pipe, means 65 including a motor and fan for creating a suction in said bowl, a closed trap chamber having the outlet of the fan communicating therewith above

the water level therein for delivering foul odors from the bowl to the trap chamber and for creating a pressure in said trap chamber, means for supplying water to a predetermined level in said chamber, and an outlet tube entirely independent 5 of the motor and fan communicating with the closed trap chamber above said water level leading to said drain pipe, whereby to conduct gases from said closed trap chamber when pressure is built up therein by said fan.

4. A toilet bowl having a drain pipe, means for creating a suction in the bowl including a fan and motor, a closed trap chamber, means for supplying water to said chamber during the flushing of the bowl, a discharge pipe entirely independent 10 of the motor and fan extending into the chamber a predetermined distance and communicating with the drain pipe for conducting gases from the trap chamber upon the building up of a pressure in said trap chamber, an inverted gooseneck disposed in said trap chamber forming a trap, and means connecting the outlet of the fan with one end of the gooseneck, the other end of the gooseneck terminating above the water level in the trap chamber, whereby upon operation of the motor 15 and fan and the creation of a suction in the bowl, a pressure will be built up in the trap chamber, whereby to vent the trap chamber through the discharge pipe, said gooseneck preventing the back flow of gases into the fan when the fan and 20 motor are inactive.

5. In a ventilated toilet including a chamber, an electric motor and a suction fan for withdrawing foul odors from the toilet bowl arranged within the chamber and entirely free from the 25 walls thereof, and coil springs connecting the motor and fan to the walls of the compartment, whereby independent movement of the motor and fan relative to the compartment is permitted.

6. In a ventilated toilet having a compartment, 30 an electric motor and suction fan unit for withdrawing odors from the toilet bowl housed within said compartment and entirely free from the walls of the compartment, vertical springs resiliently connecting the motor and fan to certain walls of 35 the compartment, and horizontal tension springs connecting the motor and fan to certain other walls of the compartment.

7. In a ventilated toilet including a bowl and a 40 flush tank, a housing arranged within the flush tank and spaced from the walls of the flush tank, resilient springs suspending the housing within the flush tank, and an electric motor and suction fan unit disposed within the housing in spaced relation to the walls thereof for creating a suction 45 within the bowl, and resilient springs suspending the motor and suction fan within the housing.

8. In a ventilated toilet having a compartment, 50 an electric drive motor and suction fan unit disposed in the compartment in spaced relation to the walls thereof, a rigid suction pipe for connection with the bowl of the toilet, a rigid outlet pipe, flexible resilient couplings connecting the outlet and inlet of the fan to said rigid pipes, and springs 55 for resiliently suspending the motor and suction fan within the compartment.

HARRY BAITHER.
